UNITED STATES PATENT OFFICE.

DAVID F. CRAWFORD, OF PITTSBURG, PENNSYLVANIA.

MECHANICAL STOKER FOR LOCOMOTIVES.

No. 905,504.

Specification of Letters Patent.

Patented Dec. 1, 1908.

Application filed August 6, 1907. Serial No. 387,297.

To all whom it may concern:

Be it known that I, DAVID F. CRAWFORD, a citizen of the United States, residing at Pittsburg, in the county of Allegheny and 5 State of Pennsylvania, have invented certain new and useful Improvements in Mechanical Stokers for Locomotives, of which the following is a specification.

My invention relates to stoking mechanism for locomotives, and has for its primary objects; to provide an under-feed stoker and grate constructed to secure a proper distribution of fuel over the grate and a proper lateral spreading from the edges of the central mass of fuel; to provide a stoker of the type indicated, having an improved arrangement whereby the supply of air to the furnace is augmented and proper combustion throughout the body of fuel on the grate 15 secured; to provide a construction wherein the fuel may be fed direct from the tender of the locomotive to the grate; to provide a construction wherein the feed of the stoker and the auxiliary draft to the furnace are 20 automatically controlled by the pressure in the boiler, and finally, to provide a stoker and grate suited to locomotive work and designed to operate effectively and economically under the widely varying and unfavorable 25 conditions incident to locomotive work. One embodiment of the invention is shown in the accompanying drawings, wherein—

Figure 1 is a central longitudinal section 30 through the fire-box and stoker;

Figure 2 is a plan view of the furnace and stoker;

Figure 3 is an enlarged transverse section 40 through the stoker and furnace, on the line III—III of Figure 1;

Figure 4 is a detail section showing the valve regulating mechanism for automatically controlling the flow of steam to the feed operating mechanism and blast, and

Figure 5 is a transverse section in an apparatus wherein a modified form of blast mechanism is employed.

Briefly stated, the apparatus comprises an under-feed means adapted to conduct the fuel from the tender to the central portion of the furnace and heap it laterally and longitudinally over the grate, together with an end drop grate and means adapted to agitate the bed of fuel and break up the edges. 55 to promote a spreading thereof. The device also includes apparatus for supplying

auxiliary draft inwardly along the edges of the furnace, together with automatic controlling means for the auxiliary blast, and automatic controlling means for the feeding mechanism.

Referring now to the drawings and the general arrangement of parts, 1 is the fire-box, a limited portion only of which is shown, 2 is the tender, the front part only 65 of which is indicated, 3 is the underfeed mechanism extending from the tender and through the center of the furnace for supplying coal to the trough 4 and heaping it upon the grate, 5 are the side grates rotatably mounted for agitating the fuel, 6 is the drop grate, 7 is the operating engine for actuating the feed mechanism, 9 are the air injectors operated from the boiler, for supplying a draft, 10 are the air chambers 70 extending longitudinally along the inner edge of each of the side grates and discharging through the twyers 11 (Figure 3) for supplying draft to the mass of fuel lying in the trough 4, and 12 is the automatic governing means regulated by the condition of the steam in the boiler, for controlling the amount of draft and the speed of the feed mechanism, which is shown in detail in Figure 4.

Any form of underfeed mechanism may be employed, but that shown is preferably used, and comprises a series of oscillating feed members 13 extending across the bottom of the feed-trough, and provided with 80 the connecting rods 14, 15, 16, and 17, and motive power is supplied by means of the engine 7 whose connecting rod 18 engages the crank 19 which is connected with one of the members 13 by means of the link 20. 95 In operating this portion of the device, coal is supplied to the device from the tender, and is gradually carried along by virtue of the oscillation of the members 13, until the front portion 4 of the trough is filled with 100 coal, and a further addition causes the material to spread out laterally and longitudinally over the grates 5 and 6. The grates 5 are, as most clearly indicated in Figure 3, of the rocking type, each side being provided with a downwardly projecting arm 21 engaging a connecting arm 22 extending longitudinally through the furnace and operable from the cab. The rocking of these 105 grates 5 breaks up the edges of the mass of material from the center trough 4, and provides for the spreading of such material over 110

the entire grate. This or some equivalent means for agitating and breaking up the edges of the mass of coal is necessary, as otherwise the surface of the coal cakes and after having moved out a slight distance upon the grate 5 further movement is arrested and an inefficient operation results. The drop grate 6, as shown, is of the rocking type, pivoted at the ends at 23, and is operated from the crankshaft 24 connected to the grate by means of the links 25 and operated by the handle 26. The movement of the side grates also serves to provide loose fuel for the drop grate, which would otherwise be insufficiently supplied at its outer edges. The feed from the side grates to the drop grate is also assisted by reason of the rearward inclination of the side grates as indicated in Figure 1. The inclination of the side grates serves also another function, in that this inclination in connection with the non-inclination of the bottom of the feed trough give a trough of increasing capacity from the rear of the furnace to the front thereof, which is desirable, as the amount of fuel which must be carried increases from the rear to the front.

The means for providing auxiliary draft also constitutes a feature of my invention, and will now be described in detail. Extending along either side of the trough 4 and across the front end of the furnace, is the air chamber 10 (Figures 1 and 3). The ends of this chamber are supplied with air pressure by means of the air injectors heretofore referred to, the steam for the injectors being supplied from the boiler by means of the pipe 27. The upper side of this air chamber 10 is connected with the twyers 11 having their openings directed transversely of the trough 4, whereby a thorough combustion at the center of the furnace is secured. The twyers may be of any desired form, but I preferably construct them as indicated, removably engaging the edge of the trough 4 on one side and the supporting bars 28 on the other side. The automatic regulating means shown in Figure 4 is employed for regulating the speed of the feed operating mechanism and the amount of blast, which regulating means is governed by the pressure of the steam in the boiler. As here shown, the pipes 29 and 30 are connected to the boiler, the pipe 31 provides steam for operating the injectors 9, and the pipe 32 supplies steam for operating the engine 7 which controls the feed of the coal. Valves 33 and 34 are provided for controlling the flow of steam to the pipes 31 and 32, and these valves are operated by the diaphragm 35 located in the casing 36. The spring 37 is provided for moving the diaphragm to its reverse position. When the locomotive is not working the pressure in the boiler of course rises, carrying the diaphragm to the

position shown, cutting off steam from the pipes 31 and 32, checking the feed of coal to the furnace, and cutting off the auxiliary blast. When the locomotive starts, the pressure on the left hand side of the diaphragm 70 is of course decreased, permitting the spring 37 to move the valves 33 and 34 to the left, opening the pipes 31 and 32, and starting the coal-feeding mechanism and the blast. In order that the blast may be started 75 slightly in advance of the operation of the coal feeding mechanism, a slip connection comprising a pin 37 working in a slot 38 is employed, the pin 37 being carried on a rod secured to the valve 34, which rod telescopes in the cylindrical projection from the valve 33 carrying the slot 38. The amount of valve opening to the pipes 31 and 32 is regulated by the pressure in the boiler, and the blast and the feed of the coal adjust 80 themselves automatically in proportion to the amount of steam being used.

In Figure 5 I have shown an arrangement for supplying auxiliary blast. In this form of apparatus each of the twyers 11' is supplied with a nozzle 9' as a substitute for the injectors 9 at the ends of the air chambers as shown in Figure 2. By this arrangement the injectors work directly to the fire instead of generating pressure in a chamber 95 which subsequently discharges it to the fire, and this modified form is more efficient than the form first described.

It will be seen from the foregoing that the type of stoker employed is readily adapted to a locomotive fire-box, that by its use the coal employed is easily carried from the tender to the furnace without handling, and that the location of the stoker is advantageous in that it is underneath the floor of 100 the cab and out of the way, and further, that it interferes in no way with the fire-door 39 (see Figure 1). The rocking grates 5 provide for a proper spreading of fuel over the entire furnace, and insure efficient service 105 from all of the grate surface. It will be understood that the term locomotive fire-box as used in the claims comprehends the use therewith of the ordinary draft means as secured by the exhaust to the stack, which draft acts particularly on those parts of the fire to which the auxiliary draft is not directed. The arrangement of the auxiliary draft provides for a proper combustion at the center of the furnace which would otherwise fail to receive a proper amount of air, and by the use of the automatic controlling means the draft is applied in the most advantageous and economical manner.

It will be understood that my invention is 115 not limited to the precise form of device shown, as, if desired, some other form of feeding device than the one shown might be employed successfully, and other means employed for agitating the coal on the side 120

125 130 135

grates 5. So far as this latter feature is concerned, my invention contemplates broadly the use of any means which will break up the body of coal upon the grate and permit it to spread. The auxiliary draft means while described as operated by live steam from the boiler, need not necessarily be so operated, as exhaust steam from the stoker engine, the pump, and even the locomotive cylinders, might be utilized, and my invention comprehends the use of steam from any source whatever. If desired, the automatic control can be regulated by the temperature of the steam instead of the pressure, my invention contemplating the use broadly of any means whatever for controlling the operation of the coal feed and the draft by means of the condition of the steam in the boiler.

Having thus described my invention and illustrated its use, what I claim as new and desire to secure by Letters Patent, is the following:

1. In a locomotive furnace, the combination with a locomotive fire box, of an under-feed mechanism extending into the furnace, a grate at the side thereof adapted to receive the fuel supplied by the underfeed mechanism, and a drop grate extending across the end of the side grate and the underfeed mechanism, the furnace being so constructed as to break up the outer edge of the body of fuel on the side grate.

2. The combination with a locomotive fire box, of an under-feed mechanism extending longitudinally therethrough, side grates in position to receive the lateral discharge from the feed mechanism, and a series of inwardly directed air passages arranged along the edges of the grates and each provided with a steam jet for supplying draft.

3. In a locomotive furnace, the combination with a locomotive fire-box, of an under-feed mechanism extending into the furnace, a grate at the side thereof sloping downwardly from the front to the rear and adapted to receive the fuel supplied by the underfeed mechanism, a grate extending across the end of the side grate and the underfeed mechanism and having a drop portion, the furnace being so constructed as to break up the outer edge of the body of fuel on the side grate. 45

4. In a locomotive furnace, the combination with a locomotive fire-box, of an under-feed mechanism extending into the furnace, a grate at the side thereof adapted to receive the fuel supplied by the underfeed mechanism, and a grate extending across the end of the side grate and the underfeed mechanism 50 and having a drop portion, the furnace being so constructed as to break up the outer edge of the body of fuel on the side grate. 55

5. The combination with a locomotive fire-box, of an under-feed mechanism extending longitudinally therethrough, side grates in position to receive the lateral discharge from the feed mechanism, auxiliary means for supplying blast to the furnace, and automatic means governed by the condition of 65 the steam in the boiler, for controlling the speed of operation of the under-feed mechanism and the blast, and adapted when the pressure in the boiler decreases to first increase the blast and then the feed. 70

In testimony whereof I have hereunto signed my name in the presence of the subscribed witnesses.

DAVID F. CRAWFORD.
